OBJECT CARRIER FOR WRAPPING MACHINE

Clarence Ouellette, East Longmeadow, Mass., assignor to Wrap-King Corporation, Holyoke, Mass., a corporation of Massachusetts

Application February 4, 1955, Serial No. 486,236

2 Claims. (Cl. 198—210)

This invention relates to improvements in wrapping machines and is directed more particularly to improvements in carriers for objects to be wrapped.

The novel features of the invention are directed to the provision of a carrier for receiving and gripping an object and a wrapper therefor which is adapted to rotate from receiving to discharging positions and vice versa in a step-by-step manner for the operation of means to act on the wrapper for folding the same.

The novel carrier is adapted for use in connection with various objects but is particularly adapted for receiving a wrapper and an object such as a head of lettuce which is somewhat frangible and variable in its dimensions.

The apparatus of the invention is characterized by a support which may be rotated on a vertical axis and which is provided with circumferentially spaced vertically disposed pockets. The pockets are arranged so that a head of lettuce with a section of wrapping material on the top thereof may be inserted upwardly through a lower end of a pocket and thereinto in its receiving position.

The support may be rotated in a step-by-step manner and the pockets are provided with gripping means which yieldingly grip the wrapper and head of lettuce.

In the step-by-step rotation of the pockets, wrapper manipulating mechanism may operate on portions of a wrapper depending from the pockets and, as the pockets move step-by-step to a discharge position, the grippers are operated to release a wrapped object.

All of the above objects, I accomplish by means of such structure and relative arrangements of parts thereof, as will fully appear by a perusal of the description below and by various specific features which will be hereinafter set forth.

To the above cited and other ends and with the foregoing and various other novel features and advantages and other objects of my invention as will become more readily apparent as the description proceeds, my invention consists in certain novel features of construction and in the combination and arrangement of parts as will be hereinafter more particularly pointed out in the claims hereunto annexed and more fully described and referred to in connection with the accompanying drawings wherein:

Fig. 1 is a plan view of a carrier embodying the novel features of the invention;

Fig. 2 is an elevational sectional view on the line 2—2 of Fig. 1;

Fig. 3 is a side elevational view of one of the pockets of the apparatus shown having an object gripping plate in association therewith; and

Fig. 4 is a side elevational view of the support and cam of the apparatus.

Referring to the drawings more in detail, the invention will be fully described.

A support 2 in the form of a plate has a hub 4 which is fixed to a hollow vertical shaft 6. A cam shaft 8 is journaled in a bearing 10 in the hollow shaft 6 and has a cam 12 fixed to the upper end thereof. The hollow

2

shaft may be rotated in a step-by-step manner and the cam shaft may be oscillated back and forth relative thereto.

Pockets 16 are provided which are tubular in form and are provided with lugs 18 which are secured to the support 2 in such a manner that the pockets are spaced circumferentially. The sides of the pockets are cut away, as at 20 for the operation of grippers, as will appear.

A plurality of posts 24 have lower ends secured to the support 2. Said posts are circumferentially spaced and extend upwardly vertically from the support 2.

A pair of gripper arms including primary and secondary arms 26 and 28 are provided for each pocket and are pivoted on adjacent posts 24. The arms of the pairs thereof carry on outer ends gripper plates 30. The plates 30 of the pairs thereof are relatively concaved on inner adjacent faces. Collars 24' are fixed to upper ends of the posts 24.

The levers 26 and 28 of each pair thereof are provided with arm portions 26' and 28' which carry intermeshing gear teeth 34, see Fig. 2.

Cam follower arms 36 are also pivoted on the posts 24. These arms 36 are disposed immediately over the levers 26, there being one such arm 36 for each pocket and each pair of arms 26 and 28. Said arms 36 are provided with slots, as shown, and screws or bolts 38 extend therethrough and are in threaded engagement with the arms 26' therebelow. The arms 36 and arms 26' may be angularly adjusted relative to one another. Cam rolls 40 are provided on outer ends of the arms 36.

The plates 30 have inner ends of outwardly extending spring anchors 44 fixed thereto. Springs 46 have opposite ends secured to the outer ends of the anchors 44 so that the plates and arms of the pairs thereof are urged towards one another whereby a wrapper and object inserted in a pocket will be yieldingly gripped.

The cam 12 has an edge portion 13 for open position of the grippers and an edge portion 15 for closed position thereof.

In describing the operation of the apparatus, it will be assumed that the shaft 6 is rotated counterclockwise in a step-by-step manner although it may be so rotated in an opposite direction.

The receiving position of the pockets may be represented by R, in Fig. 1. A head of lettuce with a wrapper on the upper side thereof may be inserted upwardly in a pocket in the receiving position thereof.

The cam 12 may be oscillated clockwise so that the gripper levers and plates 30 swing towards one another to grip the wrapper and object. The support may be rotated step-by-step either simultaneously with the action of the grippers or slightly thereafter. The relative timing of the operation of the cam and step-by-step rotation may be as desired.

As the carrier is rotated in a step-by-step manner, mechanisms may act on wrapper portions depending from the pockets.

The step-by-step movement brings the pockets to a discharge position which is represented by D, in Fig. 60 1. In this position, oscillating movement of the cam 12 brings about a separating movement of the gripper plates 30 to release a wrapped object.

It will be noted that one arm of the pairs thereof of adjacent pockets are pivoted on the same post 24 for simplicity and compactness in construction. Also to that end, the simultaneous movement of the arms of a pair is brought about by the cam actuation of one arm of the pair. The arms of each pair are arranged for simultaneous movement relative to movement of other pairs of arms. The arms of the pairs thereof are urged towards one another for gripping an object except for the

cam which is arranged according to its position to position the arms in releasing position.

The relative position of cam arms 36 and gripper arms 26 may be adjusted so as to vary the relation of the gripper plates in gripping and releasing position thereof.

While I have illustrated and described the invention as embodied in a specific arrangement, I do not intend to be limited to the details shown since various modifications and structural changes may be made without departing in any way from the spirit of the invention.

Without further analysis, the foregoing will so fully reveal the gist of my invention that others can by applying current knowledge readily adapt it for various applications without omitting features that, from the standpoint of prior art, fairly constitute essential characteristics of the generic or specific aspects of this invention, and therefore, such adaptations should and are intended to be comprehended within the meaning and range of equivalence of the claims below.

What it is desired to claim and secure by Letters Patent of the United States is:

1. Wrapping machine apparatus for receiving and gripping and releasing objects comprising, a support, a cam rotatable on a vertical axis relative to said support and having a peripheral cam edge, a plurality of posts extending vertically upwardly from and spaced equidistant peripherally of said support, a plurality of pairs of pocket forming members having outer ends arranged for gripping objects in closed positions and for receiving and releasing objects in open positions and having inner ends journalled on said posts, adjacent members of adjacent pairs of said pocket forming members being journalled on the same posts for the swinging of the members of said pairs thereof between said open and closed positions, said pocket forming members being provided with arm portions having intermeshing teeth for effecting simultaneous swinging movements of the arm portions and of the members of said pairs of pocket forming members, a cam follower arm for each of said pairs of pocket forming members having an inner end pivoted on one of said posts

and having means at its outer end engageable with the cam edge of said cam for actuating the arms of said pair, and means disposed outwardly of and connecting the outer ends of the pocket members of said pairs thereof for urging same into object gripping relation and urging said cam follower arms against the cam edge of said cam.

2. Wrapping machine apparatus for receiving and gripping and releasing objects comprising, a support, a cam rotatable on a vertical axis relative to said support and having a peripheral cam edge, a plurality of posts extending vertically upwardly from and spaced equidistant peripherally of said support, a plurality of pairs of pocket forming members having outer ends arranged for gripping objects in closed positions and for receiving and releasing objects in open positions and having inner ends journalled on said posts, adjacent members of adjacent pairs of said pocket forming members being journalled on the same posts for the swinging of the members of said pairs thereof between said open and closed positions, said pocket forming members being provided with arm portions having intermeshing teeth for effecting simultaneous swinging movements of the arm portions and of the members of said pairs of pocket forming members, a cam follower arm for each of said pairs of pocket forming members having an inner end pivoted on one of said posts and having means at its outer end engageable with the cam edge of said cam for actuating the arms of said pair, with one of the pocket members of each of said pairs thereof being disposed on a post above and adjacent a pocket member of an adjacent of said pairs thereof.
